UNITED STATES PATENT OFFICE.

ALBERT J. DOTY, OF PHILADELPHIA, PENNSYLVANIA, ASSIGNOR, BY MESNE ASSIGNMENTS, TO THE GOODWIN GAS STOVE AND METER COMPANY, OF SAME PLACE.

HEATING GAS-BURNER.

SPECIFICATION forming part of Letters Patent No. 390,352, dated October 2, 1888.

Application filed March 26, 1887. Serial No. 232,517. (No model.)

To all whom it may concern:

Be it known that I, ALBERT J. DOTY, of Philadelphia, in the county of Philadelphia and State of Pennsylvania, have invented new 5 and useful Improvements in Heating Gas-Burners, of which the following is a specification, reference being had to the annexed drawings, forming a part thereof, in which—

Figure 1 is a longitudinal section of a part 10 of a heating gas burner constructed according to my improvement. Fig. 2 is a plan view of the burner-cap, and Fig. 3 is a plan view of the disk of which the burner-top is formed.

Similar letters of reference indicate corresponding parts in all the views.

In practice it has been ascertained that the best form for an orifice for burning a mixture of gas and air is an oblong slit; but in heating gas-burners as usually constructed it is expensive and difficult to form suitable slits in the process of casting or by means of sawing.

The object of my invention is to cheaply produce a heating gas-burner top having a series of narrow radial slits for the escape of gas 25 for burning.

The invention consists in the peculiar construction and arrangement of parts, as herein-after fully described, and pointed out in the claim.

30 In carrying out my invention I take a disk, A, of sheet-iron or other suitable material, and form in the edge thereof flaring slits *a* at equal distances apart around the circumference of the disk, the slits extending inward 35 from the periphery of the disk a distance equal to the required length of the slit in the finished burner. I then, by means of suitable dies, swage up the disk so as to cause that portion containing the slits to be beveled, as shown in

Fig. 1, thus drawing together the arms *b* intermediate between the slits, and produce narrow slits having parallel edges, as shown in Fig. 1. The central portion of the disk A, I make convex, as shown in Fig. 1, if no further attachment is to be made to the burner; but in 45 case it is desired to attach a plate to the top of the burner, or if for any reason a plane surface of the disk is required, I leave the center of the disk flat.

The casting B, forming the body of the 50 burner, is of the usual shape, having the gas and air passage *c* turned upwardly at right angles at its extremity and surrounded by a conical flange, *d*, having at its periphery a lip, *e*, for receiving the edge of the disk A, as shown 55 in Fig. 1.

The disk A is centrally apertured, and secured to the casting B by a bolt, *f*, which extends downward through the bottom of the casting.

Having thus fully described my invention, I claim as new and desire to secure by Letters Patent—

The herein-described gas-burner, consisting of the body B, having the air and gas passage 65 *c* turned upwardly at its extremity, and provided with the conical flange *d*, surrounding the upwardly-turned end of the said passage *c*, and having the lip *e*, the sheet-metal burner-top A, having substantially a concavo-convex 70 form and provided with a series of slits, *a*, in its downwardly-inclined rim, and the bolt *f*, for securing the top to the body, substantially as herein shown and described.

ALBERT J. DOTY.
